Primary Examiner — Susan E Krakower*Assistant Examiner* — Jerry Shiuan-Hua Hsu(74) *Attorney, Agent, or Firm* — Eric Kelly(57) **CLAIM**

The ornamental design for a fender flare for vehicle, as shown and described.

DESCRIPTION

FIG. 1 illustrates a top perspective view of a fender flare for vehicle, intended for the right side of the vehicle, showing my new design, the opposite side, intended for the left side of the vehicle, being a mirror image thereof;

FIG. 2 illustrates a right-side view thereof;

FIG. 3 illustrates a left-side view thereof;

FIG. 4 illustrates a front view thereof;

FIG. 5 illustrates a rear (i.e., back) view thereof;

FIG. 6 illustrates a top view thereof; and,

FIG. 7 illustrates a bottom view thereof.

Broken lines in the drawings depict portions of the fender flare for vehicle that form no part of the claimed design.
